ASSORTING DEVICE

King Solomon Bobian, Montrose, Pa.

Application February 25, 1939, Serial No. 258,546

3 Claims. (Cl. 276—1)

This invention relates to an assorting device especially useful in the printing art for rapidly and accurately assorting leads, reglets and other printing accessories, such as rules, borders, etc., and has for the primary object the provision of a device of this character whereby said named printing accessories when placed on a support after their removal from use with type may be accurately and rapidly separated as to sizes and then placed in the cases or racks therefor, and consequently eliminating the present practice of manually assorting such devices by hand and similar methods which is extremely tedious work as well as adding materially to the cost of printing.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a top plan view illustrating an assorting device constructed in accordance with my invention.

Figure 2 is an end view illustrating the device.

Figure 3 is a detail sectional view taken on the line 3—3 of Figure 1.

Referring in detail to the drawing, the numeral 5 indicates a supporting panel on which may be grouped or positioned a large number of leads, reglets and other printing accessories and which are indicated by the character 6. Such devices as shown at 6 are supported on the panel 5 by a series of spacing blocks 7. It is to be understood that the devices 6 of the character described are placed on the panel 5 after being removed from use with type and naturally these devices vary as to size and in order that the devices 6 may be segregated in accordance with their sizes the present invention is employed which consists of a frame 8 consisting of end members 9 and side members 10. The side and end members are detachably connected by pins 11 insertible in a series of sockets 12 provided therefor. The connection between the side members and the end members is such as to permit the width of the frame to be readily increased and decreased as desired. Also, it will be seen that the side and end members are cut away, as shown in Figure 2, so that they may be adjustably connected by the pins 11 fitting in the sockets 12 and still rest evenly on the panel 5 with the

blocks 7 and printing accessories 6 grouped therein, as shown in Figure 1.

A rubber strip or some other cushioning material 13 is secured to the inner face of the end member 8 for the accessories 6 to engage with.

Slidable on the side members 10 is a clamping bar 13' equipped with a handle 14 located intermediate its ends and extending at right angles thereto. Braces 15 connect the handle to the clamping bar and the handle is slidably mounted 10 in spaced guides 16 carried by one of the end members 9. The guides 16 have beveled faces which coact with beveled faces on the handle 14 in slidably securing the handle on the end member 9. The clamping bar through the sliding 15 movement of the handle 14 may be moved toward and from the end member 8. Adjustably connected to the clamping bar are blocks 17 having beveled faces slidably engaging beveled faces on guides 18 carried by the end members 10. The 20 clamping bar thus connected to the end members is prevented from moving away from said end members but is free to slide endwise of said end members.

In operation, after the assembly of the accessories 6 on the panel 5 and the positioning of the frame 8 on said panel with the accessories grouped therein, as shown in Figure 1, the operator slides the handle 14 to bring the clamping bar into engagement with the accessories of the 30 larger size and with sufficient force to bind the accessories of that length or size against the end member 8 and by raising upwardly on the handle the frame will be tilted upwardly separating the accessories from the other accessories which are 35 engaged by the clamping bar so that they may be readily placed in the racks or cases therefor. In order to release the accessories clamped within the frame 8 it is only necessary to slide the handle 14 to move the clamping bar away from 40 the end member 8. This operation takes place when the frame has been positioned over the case or rack especially arranged to accommodate the accessories of that size. After the accessories have been released from the frame 8 to the rack 45 or case therefor, the frame 8 is returned to the panel 5 and the clamping bar again moved toward the end member 8 until contacting with the next size of accessories and the heretofore described operation of removing the accessories is carried 50 out.

Consequently, it will be seen from the foregoing description taken in connection with the accompanying drawing that a very efficient device has been provided wherein leads, reglets and 55

other printing accessories may be readily segregated or assorted as to sizes with speed and accuracy.

It is believed that the foregoing description when taken in connection with the drawing will fully set forth the construction and advantages of this invention to those skilled in the art to which such a device relates, so that further detailed description will not be required.

10 Having thus described my invention, what I claim is:

1. An assorting device including a supporting panel for printing accessories, a frame to be arranged on the panel with the accessories therein and engaging one side thereof, a clamping bar slidably mounted on the frame to engage and force the accessories against said side of the frame, and a handle connected to said clamping bar.
- 15 2. An assorting device including a supporting panel for printing accessories, a frame to be arranged on the panel with the accessories there-

in and engaging one side thereof, a clamping bar slidably mounted on the frame to engage and force the accessories against said side of the frame, a handle connected to said clamping bar, means slidably connecting the handle to said frame.

5 3. An assorting device including a supporting panel for printing accessories, a frame to be arranged on the panel with the accessories therein and engaging one side thereof, a clamping bar slidably mounted on the frame to engage and force the accessories against said side of the frame, a handle connected to said clamping bar, means slidably connecting the handle to said frame, means for permitting the frame to be adjusted as to size, and means for permitting the clamping bar to be adjusted to fit the frame in accordance with its adjusted sizes and including means for slidably connecting the clamping bar to said frame.

10 15 20 KING S. BOBIAN.
